COIN AND TICKET HOLDER

Sterling E. Norcross, 19 Osborne St., Bloomfield, N.J.

Filed Dec. 3, 1958, Ser. No. 777,965

8 Claims. (Cl. 206—84)

This invention relates to an article adapted to receive 15 coins of different denominations and provided with an auxiliary means for holding tickets, matches, bills or the like type media, which article is made of a material adapted to fit the contour of a surface to which it can be adhesively affixed as for example the dashboard of an automobile, and further the article is provided with an area on the face for advertising or identification purposes.

The road building programs of this era have developed many turnpikes, thruways, parkways, bridges, etc. which require in most instances that a toll or tolls must be paid to permit a vehicle a travel thereon.

In addition, in our crowded cities where parking has become a major problem, the advent of the parking meter is an accepted factor, and such meters also require coins.

In the case of the turnpikes and thruways, sometimes a single toll is paid based on a ticket which is stamped at the entrance point and collected at the exit point, while in other instances the toll is collected at various mileage stations.

The payment of these various tolls, parking fees, etc. is more convenient if the motorist has coins readily available and attempts therefore have been made to meet this problem by providing coin carriers which are connected to the vehicle at various points.

The present invention overcomes this problem by providing a combined coin carrier and ticket holder preferably, although not necessarily made of a shape conforming resilient material, adapted to be affixed to the dashboard of a vehicle; and having slot means therein to receive a plurality of coins of different denominations, and an auxiliary means to hold a ticket or a bill therein, which carrier and ticket holder is further adapted to permit its use as a novelty gimmick because there is a functional space provided therein to permit easy access to certain of the coins which space can be utilized for advertising or for identification purposes.

Accordingly, it is an object of the present invention to provide a novel coin carrier and ticket holder which can be affixed to a surface.

It is another object of the present invention to provide a coin carrier and ticket holder which has a functional space thereon for advertising or identification which permits the commercial use of this device as a novelty item.

Further objects and advantages of the invention will become evident from the following description with reference to the accompanying drawings in which:

Figure 1 is a plan view of a preferred form of the invention.

Figure 2 is a side view of the same form of the invention.

Figure 3 is a cross-section taken on line 3—3 of Figure 1.

Figure 4 is a cross-section taken on line 4—4 of 70 Figure 1.

Referring to the drawings, the coin carrier and ticket

2

holder consists of a body element or member 1 substantially rectangular in shape although it will be understood by those skilled in the art that it could be square, oval, etc. without departing from the scope of the present invention.

The rectangular shape is illustrated because the present device can be easily utilized as a novelty. For example, if it is made about the size of a business card it can merely be mailed with the business card at Christmas or on any other festive occasion as a gift.

The body member further is preferably a molded element made of sufficiently resilient material such as a polyethylene plastic so that it can easily adapt itself to the contour of a surface to which it is to be affixed as by the adhesive means 2 provided on the bottom surface thereof.

Figures 1, 3 and 4 show that the body member 1 is provided with a plurality of sized coin receiving slots as shown at 3, 4, 5 and 6 for various denominations, such as quarters, nickels and dimes, which sized slots are formed into groups disposed transversely with respect to the longitudinal line of the body member 1.

The coin receiving slots 3, 4, 5 and 6 are formed with sufficient depth, as shown in Figures 3 and 4, and are so dimensioned that they retain the coins in the holder 1 during normal oscillation or vibration of the vehicle to which the holder is attached.

Figure 1 and Figure 4 further show that between the coin receiving slots 4 and 5, a space 7 is provided. This space 7 serves a dual function. First, it provides an area to permit the placement of advertising or other commercial indicia or, for example, initials to personalize the device. Second, it facilitates the removal of coins from the coin receiving slots 4 and 5.

The function of the space as an advertising media correlates with the preferred size and shape as indicated above and makes this device a simple and ideal commercial novelty gift. The space is shown in the center but it is believed clear that coin receiving slots 4 and 5 could be grouped to one or the other edge or side of the body member and thus provide the space at a different point thereon. In addition to its coin holding function, the present device is also adapted to hold a ticket, matches, a folded bill or the like.

This is accomplished by means of a pair of spaced slots as at 8 and 9 which are formed transversely in the longitudinal sides 10 and 11 and preferably, although not necessarily adjacent one of the groups of coin receiving slots. The slots 8 and 9 have one side rounded as at 12 to facilitate insertion of the element (not shown) to be held and a groove as at 13 is also formed in the body member for the same purpose.

The use of the present device is quite simple. First, the holder is affixed to any surface by means of the adhesive means 2. Then the coin receiving slots 3, 4, 5 and 6 are filled with any desired number of coins in the denominations these slots are adapted to retain.

The paired slots 8 and 9 will hold either a bill or a toll ticket or both as conditions and the resiliency of the material forming the body member permits.

Whenever the motorist passes through a toll gate it is believed clear that adequate change or toll tickets and bills are easily available. Thus, a simple and efficient device is provided to meet the problem.

It will be understood that the invention is not to be limited to the specific construction or arrangement of parts shown but that they may be widely modified within the invention defined by the claims.

What is claimed is:

1. A coin and ticket holder comprising a body member of molded resilient material adapted to conform to the

contour of any surface, a plurality of sized coin-receiving slots in said body member formed into groups, said groups of coin-receiving slots disposed transversely of the longitudinal line of the body member, at least two of said groups in spaced relation to each other to provide an area in the upper surface of the body member for advertising and indicia elements, means comprising paired slots formed in the longitudinal sides of said body member adjacent said coin-receiving slots, and said slots rounded on one side to facilitate the insertion of a ticket and the like element.

2. In a coin and ticket holder as claimed in claim 1 wherein said spaced groups are in the central portion of the body members.

3. A coin and ticket holder comprising a body member, a plurality of sized coin-receiving slots in said body member formed into groups, at least two of said groups in spaced relation to each other to provide an area in the upper surface of the body member for advertising and indicia elements, means comprising a slot formed in the body member and adjacent one of the groups of coin-receiving slots and said slot rounded on one side to facilitate the insertion of a ticket and the like element.

4. A coin and ticket holder comprising a body member, a plurality of sized coin-receiving slots in said body member formed into groups, at least two of said groups in spaced relation to each other to provide an area in the upper surface of the body member for advertising and indicia elements, a groove for receiving matches or the like formed in the body member, means comprising paired slots formed in the longitudinal sides of said body member and said slots communicating with said groove, and said slots rounded on one side to facilitate the insertion of a ticket and the like element.

5. A coin and ticket holder comprising a body member of molded resilient material adapted to conform to the contour of any surface, a plurality of sized coin-receiving slots in said body member formed into groups, said groups of coin-receiving slots disposed transversely of the longitudinal line of the body member, at least two of said groups in spaced relation to each other to provide an area in the upper surface of the body member for advertising and indicia elements, means comprising a slot formed in the body member and adjacent one of the groups of coin-receiving slots and said slot rounded on one side to facilitate the insertion of a ticket and the like element.

6. A coin and ticket holder comprising a body member

of molded resilient material adapted to conform to the contour of any surface, a plurality of sized coin-receiving slots in said body member formed into groups, said groups of coin-receiving slots disposed transversely of the longitudinal line of the body member, at least two of said groups in spaced relation to each other to provide an area in the upper surface of the body member for advertising and indicia elements, a groove for receiving matches or the like formed in the body member, means comprising paired slots formed in the longitudinal sides of said body member and said slots communicating with said groove, and said slots rounded on one side to facilitate the insertion of a ticket and the like element.

7. A coin and ticket holder comprising a body member of molded resilient material adapted to conform to the contour of any surface, a plurality of sized coin-receiving slots in said body member formed into groups, said groups of coin-receiving slots disposed transversely of the longitudinal line of the body member, at least two of said groups in spaced relation to each other to provide an area in the upper surface of the body member for advertising and indicia elements, and means comprising a slot formed in the body member and adjacent one of the groups of coin-receiving slots for gripping and holding a ticket.

8. A coin and ticket holder comprising a body member of molded resilient material adapted to conform to the contour of any surface, a plurality of sized coin-receiving slots in said body member formed into groups, said groups of coin-receiving slots disposed transversely of the longitudinal line of the body member, at least two of said groups in spaced relation to each other to provide an area in the upper surface of the body member for advertising and indicia elements, a groove for receiving matches or the like formed on the body member, and means comprising paired slots formed in the longitudinal sides of said body member and said slots communicating with said groove and adapted to grip and hold a ticket and the like element.
